UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,963, dated July 1, 1890.

Application filed April 15, 1890. Serial No. 348,124. Term of patent 3½ years.

To all whom it may concern:

Be it known that I, HENRY O. SCHMIDT, a citizen of the United States, residing at New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, and is made larger at the top than at the bottom, and slightly below its middle it is shaped as if drawn in and encircled by an annular band of ornamental work C. The body part is mounted by a cap B of plain surface at the top, and is bounded on the bottom by an annular band D of plain

surface. Diametrically-opposite faces of the 20 body part are ornamented, as indicated at F and G, and the remaining intermediate opposite faces are relieved by the irregular ribs E, which are somewhat ornamented.

The handle is made of any suitable mate- 25 rial.

Having now described my new design, what I claim as new, and desire to secure by Letters Patent, is—

The design for cane or umbrella handles, 30 substantially as herein described and shown.

In testimony of which invention I have hereunto set my hand.

HENRY O. SCHMIDT.
